UNITED STATES PATENT OFFICE.

EMIL G. DE RY, OF SEATTLE, WASHINGTON.

SHAVED-ICE PERFORATOR.

SPECIFICATION forming part of Letters Patent No. 686,268, dated November 12, 1901.

Application filed July 24, 1901. Serial No. 69,556. (No model.)

To all whom it may concern:

Be it known that I, EMIL G. DE RY, a citizen of the United States, residing at Seattle, in the county of King and State of Washington, 5 have invented a new and useful Shaved-Ice Perforator, of which the following is a specification.

This invention relates to a shaved-ice perforator.

10 In serving certain cordials—such as creme de menthe, creme de cacao, &c.—it is customary to incorporate the cordial with shaved or finely-divided ice, this for the purpose of imparting added zest to the cordial and to render it delicate and inviting in appearance. This procedure is generally carried into effect by filling a glass with the prepared ice and then with a pencil or other implement suited to the purpose forming a well or depression in the ice into which the cordial is 15 poured, whence it permeates the mass of ice and is thereby rapidly cooled. In addition to serving as a receiver for the cordial the well also presents a convenient means to permit insertion of a straw to facilitate imbibing of the cordial. While the above procedure is effective for the purposes designed, it is objectionable on account of the amount of labor involved and the time required in its 20 summation.

It is the object of the present invention to provide mechanical means for accomplishing the procedure described, the means to be simple of construction, efficient and durable in 25 use, and easy of manipulation.

Generally stated, the invention resides in a body adapted to fit over the mouth of a glass or other vessel to contain the ice, said body carrying means to effect mechanical perforation of the ice, thereby to present a well or depression for the reception of the cordial.

The invention further consists in the novel construction and combination of parts of a shaved-ice perforator, as will be hereinafter 40 fully described and claimed.

In the accompanying drawings, forming a part of this specification, in which like numerals of reference indicate corresponding parts, I have illustrated a form of embodiment 45 of my invention capable of carrying the salient objects thereof into effect, it being understood that the structural arrangement

of the device may be departed from in shape and proportion of parts without departing from the spirit of the invention.

55 In the drawings, Figure 1 is a view in sectional elevation exhibiting the device of my invention. Fig. 2 is a similar view showing the device in operative position with relation to the glass containing ice, the view exhibiting 60 the manner in which the invention is carried into practice.

Referring to the drawings, 1 designates the body of the device, same to be constructed of any suitable material, preferably of metal, 65 and is, viewed in elevation, a hollow cone-shaped structure provided with a tubular shank 2, of any preferred length, and with an abutment 3, constituting a continuation of the shank. The bore of the shank and of 70 the abutment is engaged by a plunger 4, having at its upper end a knob 5 to facilitate the operation of the plunger and at its lower end a well-forming head or projection 6. The plunger is somewhat smaller than the bore of 75 the shank and of the abutment, and that portion of the plunger within the bore carries a coiled spring 7, having its upper end passed through a transverse opening 8 in the plunger and its lower end bearing upon a plate 9, the latter being held against the abutment 80 in this instance by screws 10. The plate is provided with a central orifice through which projects the plunger 4, the orifice to be of a size snugly to fit the plunger, thereby to guide 85 it in its movements and also to prevent the spring from working below the plane of the plate. The head 6 is held assembled with the plunger in this instance by providing the head with a threaded extension 11 to engage 90 a threaded bore in the lower end of the plunger. While the head 6 is here shown as a hemispherical structure, it is to be understood that the invention is not to be limited to this precise form, as it may be a cone-shaped pointed head of greater diameter than the plunger and still be within the scope of 95 my invention, the point being that this head in addition to performing the function of a perforator for the ice shall also act as a stop 100 to limit the upward movement of the plunger by contact with the abutment-plate 9.

The manner in which the device is employed is shown in Fig. 2, wherein a glass 12

is shown as filled with ice, and superposed over this glass is the ice-perforator, the same also being filled with ice. When the parts are thus positioned, the plunger 5 is 5 pressed to the position shown in Fig. 2, thereby forming the well or depression referred to. When pressure is released from the plunger, the same will be returned to its normal position through the agency of the spring 7, and 10 the device will then be lifted from off the glass. When the device is filled with crushed ice, as shown in Fig. 2, there will be a mound of the ice above the mouth of the glass; but it is to be understood that the device operates 15 equally well where only the glass *per se* is filled with ice, and as this will be readily understood illustration is deemed unnecessary.

It is to be understood that I do not desire 20 to have the invention limited to the particular manner of associating the returning-spring with the tubular shank and with the plunger, as herein shown, as it will be obvious that the spring may be otherwise associated with 25 these parts and still be within the scope of my invention.

Having thus fully described my invention, what I claim as new, and desire to secure by Letters Patent, is—

30 1. A device of the character specified comprising a hollow cone-shaped body and a spring-retracted plunger associated therewith, and provided with means for perforating a mass of crushed ice.

2. - A device of the character specified, comprising a hollow cone-shaped body provided with a tubular shank, and a plunger working in the shank, and a plunger-returning spring mounted on that portion of the plunger within the shank. 35

3. A device of the character specified comprising a hollow cone-shaped body provided with a tubular shank, a plunger working in the shank and having means to limit its range of motion in both directions, and a spring 45 mounted upon that portion of the plunger within the shank, and operating to return the plunger to its normal position after depression.

4. A device of the character specified comprising a hollow cone-shaped body provided near its apex with an abutment, a guide-plate secured to the abutment, a tubular shank carried by the body, a plunger housed in the shank and having its lower portion provided 55 with a head to contact with the guide-plate, and a spring mounted upon that portion of the plunger within the shank, one end of the spring being connected with the plunger and the other end bearing upon the said plate. 60

In testimony that I claim the foregoing as my own I have hereto affixed my signature in the presence of two witnesses.

EMIL G. DE RY.
